Attorney

UNITED STATES PATENT OFFICE.

AIME POLLEFEY, OF DETROIT, MICHIGAN.

MUSICAL TRANSPOSING DEVICE.

Application filed October 14, 1922. Serial No. 594,459.

My invention relates to a musical transposing device in the form of a sliding scale adapted for use in connection with any musical instrument used in orchestration.

5 The invention has for its object the provision of a transposing device, easy and simple to manipulate, and through the use of which an instrumentalist given the concert key of a musical composition can quickly determine the key in which any particular instrument should play to be in accord therewith.

10 A further object is to provide a transposing device through the use of which it is possible to transpose single instrumental parts from one kind of pitched musical instrumental part to another differently pitched instrumental part.

15 In theatrical orchestration, it is especially useful in that through its use it is possible to quickly and easily determine in what key any particular musical instrument of whatsoever pitch should play to be in accord with any given concert key. The concert key in which a musical composition is written is frequently raised or lowered to suit an individual singer's voice, or for other reason, and when advised of the new concert key, each instrumentalist is, through the use 20 of this device, able to quickly determine the proper key in which the particular instrument he is playing, should play to be in accord.

25 The invention is also useful to amateurs and students of the musical art who desire to master instrumental transposition of songs or other musical compositions, and in order to easily and quickly find the proper key signatures for each differently pitched 30 musical instrument which takes part in the orchestration. It is particularly useful to determine the proper key signatures for the cornet and clarinet, French horns and trumpets, in order to write the easiest fingering key signatures for these instruments.

35 These and other objects, together with the construction and operation will more fully appear from the following description and claims, and the accompanying drawing illustrating the device, in which:

Fig. 1 is a plan of the device.

Fig. 2 is a cross sectional view through the device.

The device, as shown, consists of two chart 40 elements, which may preferably be con-

structed as hereinafter described, and which are relatively movable so as to bring into registration the different characters carried on each.

One chart element is indicated as 5 and bears on its face the key signatures of all musical scales arranged in their natural order from the key of C, and reading from C is a clockwise direction as follows: G, D, A, E, B, and F-sharp; and reading from C in a counter-clockwise direction; F, B-flat, E-flat, A-flat and D-flat, which it will be observed, is a progressive arrangement of the keys in sharps and flats from the key of C. It will also be seen that opposite the key signatures B and F-sharp, there appear in the inner circle the key signatures C-flat and G-flat, respectively, and opposite the key signature D-flat, there appears in the same segment, but in the outer circle C-sharp. 50 The twelve key signatures forming the circle, and the three additional key signatures, requiring the same fingering as the key signatures opposite which they respectively appear, complete the fifteen key signatures 55 used in musical composition.

The movable chart element is indicated as 6 and is here shown in the form of a dial, pivoted at 7 to chart element 5 for relative rotation, and is provided with a handle 8 by means of which it may be manually rotated as desired. The key signature classification previously referred to as appearing on chart element 5 is so arranged as to appear just outside the periphery of 60 the rotatable dial, so that the musical instrument pitch groups inscribed at determined intervals within the circumference of the dial may be brought into registration with the different key signatures of the 65 chart as the dial is rotated, and as appears from the drawing.

The rotatably mounted dial bears on its face, a classification by groups of the differently pitched musical instruments used in 70 orchestration, and which groups are so arranged as to coordinate with the key classification on the chart. In arranging the nine different pitch groups on the dial, the F-horn group has been placed in the center of 75 the list, as the F-horn is the highest in pitch of the horn family and the F-trumpet is the lowest in pitch of the trumpet family. To the right of the F-horn group on the dial appear the four differently pitched groups 80

of musical instruments having the flat sign, namely B-flat, E-flat, A-flat and D-flat; and to the left of the F-horn group on the dial appear the names of the four differently pitched groups having the natural sign, namely, C, G, D, and A, respectively.

The twelve key signatures, which appear in the circle on the chart, and the three key signatures requiring corresponding finger-
ing which appear in the concentric circle, register with the groups listed on the dial, so that if for example, the C instrument group is moved into registration with any key signature in the outer circle, the remaining differently pitched groups on the dial register with the proper key signature so as to be in accord therewith. This accordance for orchestration between the groups on the dial and the key signatures on the chart, will, irrespective of the position to which the dial may be moved, be the result. If it is desired to play a musical composition in another key than that in which written, given the new key signature of the concert instruments, it will be possible to find the proper key signature for any other instrument or pitch group, through the use of my device as described; to-wit, merely by moving the dial to bring the C group into registration with the new key signature at which time all the remaining instrument groups will be in registration with the proper key signature to be in accord therewith.

35 What I claim is:—

1. In a device of the class described, a sliding scale comprising a chart element bearing on its face the key signatures of all the scales used in musical composition arranged in their natural order from the key of C, and an element bearing on its face reference characters designating the differently pitched groups of musical instruments used in orchestration, said elements movable relatively so as to bring the reference characters indicating the different groups into registration with the different key signatures of the chart, said group pitch characters so relatively arranged that when the C group is brought into registration with any signature key on the chart the remaining group characters register with the proper key signatures on the chart to be in accord therewith.

50 2. In a device of the class described, in combination, a chart element bearing on its face all the key signatures used in musical composition arranged in a determined relative order, a dial element bearing on its

face a key classification of the differently pitched groups of musical instruments so arranged that when the reference character indicating the C group of instruments is brought into registration with any key signature of the chart the remaining key reference characters of the dial register with the proper key signatures of the chart to be in accord therewith. 60 65

3. In a device of the class described, in combination, a chart, a dial pivoted thereto for rotation, said chart bearing on its face the key signatures used in musical composition arranged in their natural order from the key of C, said dial bearing on its face a key classification of the differently pitched groups of musical instruments reversely arranged from C as a base in such a manner that when the dial is so rotated as to bring the C group into registration with any key signature of the chart the remaining groups register with the proper key signature on the chart for such group to be in accord with the C instrument group. 70 75

4. In a device of the class described, in combination, a chart, a rotatable dial pivoted to said chart, said chart bearing on its face in spaced apart relationship about the periphery of the rotatable dial a classification of the fifteen different signature keys used in musical composition arranged in twelve groups as follows: reading in a clockwise direction C, G, D, A, E, B, and C-flat, F-sharp or G-flat, C-sharp or D-flat, A-flat, E-flat, B-flat and F, and said dial bearing on its face a key classification of the differently pitched groups of musical instruments used in orchestration peripherally arranged to register with the keys on the chart and arranged in a clockwise direction as follows: 80 85 C, F, B-flat, E-flat, A-flat, D-flat, A-sharp, D, and G. 90 95 100

5. A device comprising a pair of relatively movable members adapted to be brought into registry with each other in different positions and each having a series of equally spaced sections, the sections of one member bearing the indicia of the various musical keys so arranged that the keynote of each key is the fifth or dominant note of the key immediately adjacent in a given direction, and the sections of the other member bearing the indicia of the keys so arranged that when read in the same direction the keynote of each key is the fourth or subdominant note of the adjacent key. 105 110
